UNITED STATES PATENT OFFICE.

JAMES QUINCY LEAVITT, OF OGDEN, UTAH, ASSIGNOR OF ONE-HALF TO HERBERT L. HERRINGTON, OF OGDEN, UTAH.

LABELING-MACHINE.

1,388,728.

Specification of Letters Patent. Patented Aug. 23, 1921.

Application filed August 20, 1920. Serial No. 404,811.

To all whom it may concern:

Be it known that I, JAMES Q. LEAVITT, a citizen of the United States, and a resident of Ogden, in the county of Weber and State 5 of Utah, have invented a new and Improved Labeling-Machine, of which the following is a full, clear, and exact description.

This invention relates to improvements in labeling machines, an object of the invention being to provide improved means for applying labels to the ends of cans.

A further object is to provide improved means for feeding the cans onto a track and provide improved means for moving the 15 track vertically so that the cans receive first a daub of paste, then a label and then a smoothing or pressure brush to firmly apply the labels to the cans.

A further object is to provide improved 20 mechanism for controlling the movement of the cans, the application of the paste, the application of the label, and the smoothing or pressing operation, all of said mechanisms operating in unison and simultaneously, the 25 several operations taking place at different stations.

A further object is to provide a machine of the character stated embodying novel details and combinations of parts, all of which 30 will be more fully hereinafter described and pointed out in the claims.

In the accompanying drawings—

Figure 1 is a view in front elevation illustrating my improved machine, showing the 35 can track elevated and the cans in position for receiving the paste label and smoothing and pressure brush.

Fig. 2 is a top plan view.

Fig. 3 is a view in rear elevation, the parts 40 being in the same position as shown in Fig. 1.

Fig. 4 is an end elevation.

Fig. 5 is a view in longitudinal section on the line 5—5 of Fig. 2.

Fig. 6 is a fragmentary view in longitudinal section on the line 6—6 of Fig. 2.

Fig. 7 is a sectional plan view taken on the line 7—7 of Fig. 1.

Fig. 8 is a view in transverse section on the line 8—8 of Fig. 1.

Fig. 9 is an enlarged fragmentary view in transverse section on the line 9—9 of Fig. 1.

Fig. 10 is an enlarged fragmentary view in section on the line 10—10 of Fig. 1.

Fig. 11 is a bottom view of the label container shown in Fig. 10. 55

A represents a stationary openwork frame which constitutes the main support of my improved machine. A motor 1 preferably forms a part of the machine or, of course, 60 the machine may be driven from any desired source of power.

The motor 1 is supported at the base of frame A and the drive pulley 2 of the motor is connected by a belt 3 with a large pulley 4 on a transversely positioned shaft 5 supported in the frame A. A pinion 6 on shaft 5 transmits motion to a gear wheel 7 on the main shaft 8 of the machine. This shaft 8 is positioned transversely of the frame A and 70 operates to drive all of the movable parts of the machine.

A vertically movable track B is supported in the upper portion of the frame A and, as shown most clearly in Fig. 9, consists of a 75 pair of angle iron rails 9, 9, having side frames 10 secured thereto, and said rails and side frames supported on transverse bars 11 having slots 12 therein for the reception of screws or bolts 13 with clamping nuts 14 80 below to secure the rails and frames at any desired distance apart to facilitate the adjustment of the track to accommodate cans C of any diameter.

The end bars 11 of the track B are secured 85 to and supported on the upper ends of vertical rods 15, the latter guided in perforated brackets 16 on frame A and having collars 17 secured thereon. These collars 17 are engaged by the bifurcated outer ends 18 of 90 levers 19, the said bifurcated portions 18 straddling the rods 15 below the collars 17.

The levers 19 are pivotally supported near their outer ends as shown at 20, and at their inner ends are perforated for the reception 95 of lugs 21 on the outer ends of links 22. Coiled springs 23 are located around the lugs 21 and against the levers 19 and nuts 24 are positioned on the upper ends of the lugs and permit of a certain amount of adjustment to 100 give the necessary cushion compensating connection between the parts.

The lower ends of the links 22 are pivotally connected to an arm 25 which is pivotally supported by the frame A as shown at 26, 105 and a cam 27 on the main drive shaft 8 engages the upper face of this arm or lever 25 and imparts downward movement to the

same. When the lever 25 is moved downwardly, the outer ends of the levers 19 are forced upwardly through the medium of the links 22 connecting the levers 25 and 19, 5 and said movement of the levers 19, through the medium of the rods 15, operates to elevate the track B and the can C thereon.

A conveyer belt D is located at one side of and at the entrance end of the machine and 10 is supported on pulleys 28 and 29 on shafts 30 and 31 respectively. The shaft 30 is connected by beveled gears 32 with a vertical shaft 33 and the latter is connected by beveled gears 34 with a horizontal shaft 35, 15 said shaft 35 being connected by beveled gears 36 with the main drive shaft 8 so that motion is imparted through the said shafts and gears to operate the conveyer D.

It is, of course, to be understood that each 20 of said shafts will have suitable mounting in the frame A and the beveled gears will be fixed to the shafts so that motion will be transmitted from the main shaft 8 to the conveyer D.

25 This conveyer D is located at the entrance end of the machine and extends across the entrance end of track B and receives the cans in a vertical position from a twist chute 37 to which the cans are supplied in any 30 proved manner. Ordinarily the cans are fed in horizontal position, and hence, a twist, such as shown at 37, is necessary to bring the cans to an upright or vertical position and deposit them on the conveyer D, and 35 guide frames 38 are provided at the sides of the conveyer to prevent lateral displacement of the cans during their movement on the conveyer.

It will be noted particularly by reference 40 to Fig. 2 that the cans C on the conveyer D are moving at a right angle to the cans C on the track B. The movement of the cans on the conveyer D is limited by an extension 39 on one of the side frames 10 of the track 45 which extends across and above the conveyer D and stops the cans against further movement on the conveyer.

The cans are fed step-by-step along the track B by forcing a can from the conveyer 50 D onto the track at each step-by-step operation. This operation is performed by means of an angle arm 40 which is adjustably secured to a longitudinally movable rod 41 by means of a bracket 42. This rod 41 is movable at one end in a guide bearing 43 and at its other end is bifurcated and provided with a pair of rollers 44 between which the upper end of a lever 45 is positioned. The lower end of this lever 45 is fulcrumed on a 55 rod 46 mounted in the frame A and a coiled spring 47 connects the lever 45 with the frame A and holds the latter in normal position.

A cam 48 on the main shaft 8 is adapted 60 to engage the lever 45 and force it to the

right of Fig. 1, thus moving the rod 41 to the right and moving the angle arms 40 in a direction to force the can C from the conveyer D onto the track B and during this movement push the whole line of cans on the 70 track a distance of one can and eject a can at the discharge end of the track into a suitable guide or chute 49, from which the cans are conveyed or moved to any desired point of discharge. 75

It will be noted that the angle arm 40 has a relatively long member 50 which operates to hold back the cans on the conveyer D and permit, or rather compel but a single can to move from the conveyer D onto the track 80 B at each operation of the arm.

Above the track B and in position to be engaged by the cans C when the latter are elevated, I provide a dauber E, a label receptacle F and a rotary brush G spaced 85 apart the proper distance so as to exactly center with the cans and be engaged in turn by the cans as they are moved step-by-step from one station to another.

The dauber E is carried by a bar 51 moving 90 transversely across the upper portion of the frame A and preferably between rollers 52 carried by bracket arms 53 on the frame. The dauber E may be adjustable vertically and I have indicated a simple 95 form of adjustable means consisting of a screw threaded handle 54 on the dauber having adjusting nuts 55 above and below the bar 51. A pin 56 on the bar 51 is adapted to engage the rollers 52 and limit the forward 100 movement of the dauber.

The forward portion of the bar 51 is movable between a pair of uprights 57 secured to brackets 58 on frame A and is pivotally connected, as shown at 59, to a relatively 105 long bowed lever 60. This lever 60 is fulcrumed in frame A as shown at 61, and is engaged by a cam 62 on the shaft 35 to move the lever 60 in one direction, and a coiled spring 63 connects the lever 60 with an arm 110 64 on bracket 58 to move the latter in the opposite direction.

65 represents a paste cup or receptacle having a paste roller 66 therein adapted to be engaged by the dauber E and supply paste 115 to the dauber when the latter is moved to its rearward position as indicated in Fig. 8. The paste roller 66 is secured upon a shaft 78 which is continuously revolved. This shaft 78 is connected by beveled pinions 79 to a vertical shaft 80 and the latter connected by beveled pinions 81 with the main shaft 8 so that motion is continuously imparted to the paste roller. 120

At each step-by-step operation of the machine the dauber E is caused to move rearwardly by the spring 63 when permitted by the cam 62 so that the dauber moves from a position above the cans C to a position over and in contact with the paste roller 66 130

- to receive a supply of paste therefrom, and as the cam 62 revolves, it will engage the lever 60 and force the dauber E back to normal position above the cans and in position 5 to contact with a can when the track is elevated so as to supply a daub of paste to the end of the can. This daubing operation constitutes the first station of operation of the machine.
- 10 After the can has received this daub of paste, it is moved under the label supply receptacle, and when the can moves upwardly, it will contact with the lowest label 67 and when withdrawn, will carry the label on the 15 can because of the adhesive which has already been applied to the end of the can.
- The labels 67 are supported in a pile or column in the container F and are fed downwardly by means of a follower 68 and as the 20 particular construction of this label feeding device forms the subject matter of a separate application, it will not be described in detail in this application except to say that the labels are fed downwardly and the lowest 25 label is removed by reason of the contact with the adhesively daubed can coming in contact therewith.
- The rotary brush G is supported in a rotary sleeve 69 having mounting in a bracket 30 70 on an upright frame 71, and the brush G is vertically adjustable in the sleeve in any desired manner and I have illustrated a simple form of jam screw 72 for the purpose. A pulley 73 is fixed to the sleeve 69 and is connected by an endless belt 74 with a pulley 75 on the vertical shaft 33 so that rotary motion is supplied continuously to the brush G and the latter operates to press on and smooth the label so that it is firmly and 40 smoothly affixed to the can.
- As it is desirable to adjust the machine for the accommodation of cans of different sizes, it is necessary to provide a mounting whereby the container F and rotary brush 45 G can be adjusted longitudinally of the machine. A simple means of adjustment is to provide slots 76 in the frame 71 and secure the supports for the brush and the container to the frame by means of bolts 77 projected 50 through these slots.
- The arm 40 above referred to is adjustable relative to its supporting bracket 42 to exactly position said arm in accordance with the diameter of the cans and as above described, the track B is adjustable to receive cans of different sizes, hence, I am enabled with my machine to paste labels on the ends of cans of any ordinary size by merely adjusting the parts to suit.
- 60 The operation is as follows: The cans C are fed onto the conveyer D and are moved thereby until coming into contact with the extension 39 of one of the side frames 10 of track B. The conveyer D is continuously 65 driven through the medium of the main shaft 8, beveled gears 36, horizontal shaft 35, beveled gears 34, vertical shaft 33, beveled gears 32, and shaft 30 on which one of the conveyer pulleys 28 is fixed.
- One can at a time is moved from the conveyer D onto the track B by means of the angle arm 40, and the movement of this angle arm 40 is caused by the engagement of the cam 48 with the lever 45, the latter moving the rod 41 longitudinally and with it the arm 40 to move a single can onto the track and force the line of cans longitudinally of the track to eject a can from the discharge end thereof, and during this operation the extension 50 serves to hold back the cans on the conveyer D.
- After each step-by-step movement of the cans, the track B is caused to elevate, and this operation is as follows: The cam 27 on main shaft 8 engages lever 25 and forces the latter downwardly and, through the medium of the links 22 and levers 19, the rods 15 are moved upwardly, thus bringing the cans in contact with the dauber E, container F, and rotary brush G. Thus the cans in turn receive a daub of paste from dauber E, then a label from the container F and are then brought in contact with the rotary brush G to smooth and press the label into engagement with the can.
- During the movement of the track B downwardly and before it is again returned to its upright position, the dauber E is caused to move transversely of the machine and receive a supply of paste from the paste roller 66. This movement of the dauber E is first caused by the spring 63, the cam 62 permitting such operation, so that the spring 63 will move the dauber E to a position over and in contact with the paste roller 66. As the cam 62 revolves, it will engage the lever 60 and force the dauber E back to a position over a can ready for the next elevation of the track.
- It will thus be noted that the dauber E, container F, and rotary brush G have stationary stations and with the can are moved vertically by the track so that the labels can be applied at each operation, but in succession, to the cans as they are fed longitudinally of the track.
- Various slight changes might be made in the general form and arrangement of parts described without departing from the invention, and hence I do not limit myself to the precise details set forth, but consider myself at liberty to make such changes and alterations as fairly fall within the spirit and scope of the appended claims.
- I claim:
1. A can labeling machine, comprising a dauber, a label receiving and a pressure device spaced apart and held against vertical movement, a can supporting track below said label affixing devices, means for moving

125
130
135

the track upwardly to position the cans thereon in contact with the dauber, a label in the receptacle and the pressure device, a can conveyer at right angles to the entrance end of the track, and means for forcing a single can from the conveyer onto the track and thereby moving all of the cans on the track a distance of one can at each operation.

10 2. A can labeling machine, comprising a dauber, a label receiving and a pressure device spaced apart and held against vertical movement, a can supporting track below said label affixing devices, means for 15 moving the track upwardly to position the cans thereon in contact with the dauber, a label in the receptacle and the pressure device, a paste supply device, and means for moving the dauber into engagement with 20 the supply device and then into position for engagement with a can.

3. A can labeling machine, comprising a dauber, a label receiving and a pressure device spaced apart and held against vertical 25 movement, a can supporting track, means for moving the track vertically to position the cans thereon in contact with the dauber, a label in the receptacle and the pressure device, a pair of levers pivotally supported 30 between their ends and at their outer ends operatively engaging the track, a cam operated lever, and links connecting the cam operated lever with the first-mentioned levers, whereby the movement of said levers causes a vertical movement to be imparted 35 to the track.

4. A can labeling machine, comprising a dauber, a label receiving and a pressure device spaced apart and held against vertical 40 movement, a can supporting track, means for moving the track vertically to position the cans thereon in contact with the dauber, a label in the receptacle and the pressure device, means for forcing the cans longitudinally of the track in a step-by-step movement, a pair of levers pivotally supported 45 between their ends and at their outer ends operatively engaging the track, a cam operated lever, and links connecting the cam operated lever with the first-mentioned levers, whereby the movement of said levers causes a vertical movement to be imparted 50 to the track.

5. A can labeling machine, comprising a dauber, a label receiving and a pressure device spaced apart and held against vertical 55 movement, a can supporting track, means for moving the track vertically to position the cans thereon in contact with the dauber, a label in the receptacle and the pressure device, a can conveyer at right angles to the entrance end of the track, means for forcing a single can from the conveyer onto the track and thereby moving all of the cans on 60 the track a distance of one can at each op-

eration, a pair of levers pivotally supported between their ends and at their outer ends operatively engaging the track, a cam operated lever, and links connecting the cam operated lever with the first-mentioned levers whereby the movement of said levers causes a vertical movement to be imparted 70 to the track.

6. A can labeling machine, comprising a dauber, a label receiving and a pressure device spaced apart and held against vertical movement, a can supporting track, means for moving the track vertically to position the cans thereon in contact with the dauber, a label in the receptacle and the pressure 80 device, a paste supply device, means for moving the dauber into engagement with the supply device and then into position for engagement with a can, a pair of levers pivotally supported between their ends and at 85 their outer ends operatively engaging the track, a cam operated lever, and links connecting the cam operated lever with the first-mentioned levers whereby the movement of said levers causes a vertical movement to be 90 imparted to the track.

7. A can labeling machine, comprising a frame, a vertically movable track on the frame, means for compelling the movement of cans on the track a distance of one can 95 at each operation thereof, a paste dauber, a label receptacle, a rotary brush supported above the track and in position to be engaged by the cans when the track is elevated, a paste receptacle at one side of the track, a 100 paste roller in the receptacle, and means for moving the dauber from its position over the cans into engagement with the roller.

8. A labeling machine, comprising a frame, a vertically movable can supporting track on the frame, a dauber, a label receptacle, a rotary brush above the track in position to engage the cans when the track is elevated, a conveyer located across the entrance end of the track, an angle arm adapted to move across the conveyer and force a can from the conveyer onto the track, and an extension on said arm adapted to hold the other cans on the conveyer against movement during the said operation.

9. A can labeling machine, comprising a frame, a vertically movable track in the frame, a dauber, a label receptacle, a rotary brush above the track in position to engage the cans when the track is elevated, means 120 for feeding one can at a time onto the track and moving the line of cans thereon a distance of one can, a paste receptacle, and means for moving the dauber from its normal station into engagement with the paste 125 receptacle and back to its normal station.

10. A can labeling machine, comprising a frame, a vertically movable track in the frame, a dauber, a label receptacle, a rotary brush above the track in position to engage 130

the cans when the track is elevated, means for feeding one can at a time onto the track and moving the line of cans thereon a distance of one can, a paste receptacle, means 5 for moving the dauber from its normal station into engagement with the paste receptacle and back to its normal station, said last-mentioned means comprising a bar extending transversely of the frame and supporting the dauber, a lever connected to said bar, a cam engaging said lever for forcing it in one direction, and a spring engaging said lever for moving it in the opposite direction.

10 11. A can labeling machine, comprising a frame, a track on the frame consisting of a pair of angle iron rails, side frames secured to the rails, supporting bars for the rails, vertical rods on which certain of said 15 supporting bars are secured, levers operatively engaging the rods for moving the track vertically, and label affixing devices above the track and with which the cans are moved into operative position when the 20 track is moved upwardly.

12. A can labeling machine, comprising a frame, a track on the frame consisting of a pair of angle iron rails, side frames secured to the rails, supporting bars for the 25 rails, vertical rods on which certain of said supporting bars are secured, levers operatively engaging the rods for moving the track vertically, said track and side frames having adjustable securing means connect- 30 ing the same to said bars, and label affixing

devices above the track and with which the cans are moved into operative position when the track is moved upwardly.

13. A can labeling machine, comprising a frame, a dauber, a label receptacle, a rotary 40 brush supported on the frame, means permitting adjustment of said rotary brush and receptacle whereby the parts may be arranged to center with different diameters of cans, means for supplying cans in vertical 45 position onto the track, and means for moving the track vertically into contact with the dauber, the label in the receptacle, and the rotary brush.

14. A can labeling machine, comprising 50 a frame, a vertically movable track on the frame, means for directing cans in vertical position onto the track, a label receptacle above the track having labels therein adapted to be pasted on the ends of the cans, a 55 dauber at one side of the receptacle, and a rotary brush at the other side of the receptacle.

15. A can labeling machine, comprising a frame, a vertically movable track on the 60 frame, means for supplying cans in vertical position to said track, a dauber, a label receptacle, a rotary brush above the track, a paste supply device, means for moving the dauber from position over the track into 65 engagement with the paste supply device, a main shaft in the frame, and means for imparting motion from said main shaft to all the movable parts of said machine.

JAMES QUINCY LEAVITT.
